UNITED STATES PATENT OFFICE

HUGH W. SANFORD, OF KNOXVILLE, TENNESSEE

MINE CAR

Application filed September 17, 1930. Serial No. 482,616.

This invention relates to the manner of supporting the body of a mine car on the wheel axles, the wheels being supported on the track rails and the wheels supporting the axles and the axles supporting the car body, and the wheels being "loose" or rotatable on the axle.

A major object of the invention is to make provision:

- 10 (1) for normally holding the axles against endwise movement in their bearings relative to the car body, in order that the inner ends of the wheel hubs may not thereby be given end thrust against the adjacent stationary part of the car, the wheels being thus given freedom for rotation and freedom from wearing contact with the adjacent stationary part of the car; (2) for removal of the axles endwise through their bearings without necessity for detaching and later re-attaching the bearings; (3) for downward movement of one end of an axle in the axle bearing when, during movement of the car, that bearing is at more than normal height above the adjacent track rail; (4) and for partial rotation of each axle when an end thereof is in movement below normal position.

In connection with the foregoing statement of objects, it is to be noted that in mine operation, the rail tracks on which the mine cars travel are of such irregular and unsubstantial construction and with such grades as result in severe wear and strains on the cars. And now to attain larger capacity, cars themselves and their loads are heavier. Consequently, practically all strains incident to operation are increased. Hence structural features tending to reduce wear and to prevent breaking or distortion are desirable; and provision for removal of parts for straightening or replacing is desirable. For example, the provision herein described for removal of the axles without disturbing the axle bearings is important.

In a preliminary way, let it be noted that, in my improvement, adjacent each wheel, each axle is normally engaged in a bearing which holds the axle, when in normal position, against endwise movement and which bearing is larger than the diameter of the part

of the axle which rests in the bearing, whereby that part of the axle is free to drop when the adjacent part of the car is high relative to the track rail under said wheel. If in such case, that end of the axle does not drop, that wheel is held out of engagement with the adjacent rail. Provision for downward movement of that end of the axle and that wheel, by gravity, allows the wheel to remain in full engagement with the adjacent rail. Thereby the four wheels constantly remain in working engagement with the track rails. During such movement of the axle below normal position, engagement between the axle and the bearing causes partial rotation of the normally non-rotary axle.

In the accompanying drawings,

Fig. 1 is a longitudinal upright section along the axial line of an axle, an axle bearing and a wheel hub, the axle being shown in normal position in the bearing;

Fig. 2 is an upright transverse section on the line, 2—2, of Fig. 6, looking toward the right;

Fig. 3 is an upright transverse section on the line, 3—3, of Fig. 1, looking toward the left;

Fig. 4 is an upright transverse section on the line, 4—4, of Fig. 1, looking toward the right;

Fig. 5 is an upright transverse section on the line, 5—5, of Fig. 1, looking toward the right;

Fig. 6 is a detail perspective of the bearing casting detached from other parts;

Fig. 7 is a detail sectional view showing a part of the structure of Fig. 1, the axle being in the lower part of the bearing;

Fig. 8 is a view similar to Fig. 7, the axle being in position for endwise movement through the bearing.

Because in such cars the two axles are alike and the ends of each axle are alike and the four bearings by which the axles support the car body are alike, it is deemed sufficient to illustrate and describe only one bearing and parts associated therewith.

Referring to the drawings, B is a side member constituting a fixed part of the car body. In the form shown by the drawings, this mem-

ber is a longitudinal metal channel having outward-directed flanges, B1. For an illustration of a car body having such a channel member at each side of the car, reference is 5 here made to Letters Patent of the United States No. 1,607,565, granted to me November 16, 1926. In that patent the channel-form side sills are connected to each other by end sills or end structures. It is to be understood that the side members, B, are similarly 10 joined in the present car.

In the drawings, the upright web of the channel member, B, is apertured to receive the bearing casting, C. That casting consists of an upright plate placed between the flanges, B1, of the member, B, and against the adjacent face of the web of that member, and the casting consists further of a lateral extension, C1, reaching through the upper part 15 of the opening, B2, in the member, B. The bearing casting, C, and the channel member, B, are secured to each other by means of rivets, D, extending horizontally through those members. Those rivets are preferably countersunk in the bearing casting, as shown in 20 Fig. 2 of the drawings.

The inner working face of the bearing is curved to conform to a part of the upper half of the journal, A1, of the axle, A, so that the 25 bearing will normally rest saddle-fashion on the journal. To make engagement between the journal and the bearing to hold the bearing against relative endwise movement on the journal, the working face of the bearing is 30 provided with a groove or channel, C2, and the journal is provided with a circumferential collar or rib, A2, normally extending into that channel. The side faces of the channel, C2, are made slanting to facilitate seating the 35 collar, A2, in the channel during relative upward movement of the journal in the bearing. Making this engagement between the journal and the bearing avoids pressure of the inner 40 end of the wheel hub, E1, against the adjacent face of the bearing, C, through relative axle end thrust. Thus the wheel is left free 45 on the journal.

The opening, C3, in the bearing casting extends downward far enough to allow the axle 50 to move downward automatically as far as is needed to maintain engagement of the wheel with the track rail during ordinary operation of the car. The lower part of the opening, B2, in the member, B, is to conform approximately 55 to the lower part of the opening, C3, in the bearing casting, C. (See Figs. 1, 7 and 8). Furthermore, the lower part of the opening in the bearing casting and the lower part of the opening in the member, B, are 60 to be large enough to allow relatively moving the journal including the collar or rib, A2, endwise through the member, B, and the bearing casting after that end of the car has been raised and the axle has been lowered sufficiently 65 to free the collar, A2, from the chan-

nel, C2. In this manner, after one of the wheels has been removed from the axle, the entire axle may be removed endwise through the adjacent bearing castings without removing the bearing castings from the channel member, B2.

In the form shown by the drawings, the part of the journal which is to receive the wheel, E, is of ordinary form, and the hub, E1, of the wheel is of simple form, roller bearings being omitted. A cotter-form cross pin, E2, extends through the journal adjacent the outer face of the hub for retaining the hub on the journal. The casting, C, may form an abutment for the inner end of the hub.

It being assumed that, during normal operation of the car, the wheels freely rotate on the journals, and that the axles are at rest in the bearing castings, C, it is desirable 55 to impart to the axles occasional partial rotation, in order that the wearing faces of the journals, the parts resting in the lower part of the wheel hubs, may be changed. That is for the purpose of avoiding excessive wearing of one part of the circumferential faces 60 of the journals.

I have shaped the interior faces of the bearing casting to automatically effect such 65 partial rotation of the axle during downward or upward movement of one end of the axle. For this reference is made to Figs. 1 and 3.

The part of the bearing which is in contact with or seats on the journal when the 70 journal is in the upper position—the position of rest, may be termed the bearing seat. The interior part of the bearing below the bearing seat is larger than the diameter of the journal, preferably larger than any part 75 of the entire axle. When the journal is descending from its normal position and the car is in endwise motion, the journal and the adjacent wheel tend to lag back on the rail track. Thereby the journal is drawn 80 against what is then the rear face of the enlarged part of the bearing. During the 85 downward movement of the journal, this tends to produce a rolling of the journal on that face of the bearing. When the car is still in motion in the same direction and the 90 relative height of the adjacent track rail increases whereby the journal is lifted by the adjacent wheel, that lifting is in contact 95 with the same interior bearing face and there is tendency to roll the journal in the direction opposite the tendency to roll during downward movement of the journal. It is 100 to be noted that only slight rolling or turning of the axle is sufficient; because repeated short fractional turns will in time cause complete rotation or turning of the axle, whereby all parts of the circumferential face 105 of the journal are made to seat in the lower part 110 of the bearing.

of the wheel hub, E1, to take wear from that part of the hub.

Even if the side faces of the bearing are regular, there is such tendency for rolling of the axles; but that tendency is increased if those faces are made irregular so as to make more definite engagement with the journal during its upward or downward movements, especially during upward movement. Figs. 3, 4 and 5, show those faces irregular. In those figures, at each side of the bearing, faces meet to form a rib, C4, parallel to the bearing axis, and two faces meet to form a rib, C5, parallel to the bearing axis. Below each rib, the face is sufficiently inclined toward the upright axial plane of the bearing to tend to arrest the upward movement of the journal when at that side of the bearing. Each of those inclined faces will tend to cause partial turning or rolling of the journal during upward movement of the journal into its normal position.

It is to be observed that the upper part of the opening, B2, in the web of the channel member B, does not make contact with the journal during the upward or downward movements of the journal; for that web extends over the bearing casting extension, C1. The lower part of the opening in said web may be even with or lower than the lower part of the opening, C3, in the bearing box casting.

Let it be remembered that in normal service only one end of the same axle moves downward in its bearing casting. Hence the collar, A2, on the journal at the other end of the axle will remain in engagement in the adjacent groove, C2. Thereby endwise movement of the axle is prevented, and the low end of the axle is kept in position to rise and bring its annular collar, A2, into the adjacent groove, C2. For removal of an axle, that end of the car is to be raised by jacks so as to lift both bearings to leave the axle journals in the lower and larger parts of the bearings and free from both bearing grooves, C2.

Normally, at each of the four bearings, the rib, A2, is in engagement with the adjacent groove or channel, C2. Thus each axle, through that engagement, tends to hold the axle castings and the body side members, B, from moving toward or from each other. Even if one end of one axle is down, the other axle is thus in engagement with both members, B, for preventing movement of the members, B, toward or from each other.

If the construction of the body of a car is such as to render it unnecessary to in this manner hold the side members from moving toward or from each other, the groove-form engagement of the journal may be changed, so that in one bearing the journal is engaged to prevent axle movement in one direction while engagement in the other journal prevents axle movement in the other direction;

but the engagement in each bearing should prevent movement of the axle in the direction of the other bearing. That would prevent movement of the wheel adjacent the engaged bearing from moving away from the adjacent rail. The other end of the axle would be low to allow the adjacent wheel to rest on the adjacent rail and keep its flange in engagement with the inner face of the adjacent rail head.

By way of summary, let it be noted that my improved car contains these important provisions: (1) for holding the axles against endwise movement in the axle bearings; (2) for leaving the wheel hubs free from axle thrust engagement; (3) for allowing removal of the axles endwise through the bearings without cutting rivets or otherwise detaching the bearings; (4) for allowing either end of the axle to drop when the adjacent wheel is over a relatively low part of the adjacent track rail, and (5) for imparting partial rotation to the axle when one end thereof is in movement below normal position.

It is to be remembered that pressure of the inner end of the wheel hub against an adjacent part of the car body may, in the absence of means for preventing, come in either of two ways.

The first of those two ways is axle thrust—horizontal movement of the axle in the axle bearings. The engagement of the axle in the axle bearings to prevent endwise movement of the axle in the bearings has been herein described as one of the features of my present invention.

The second form of hub pressure against the car body is indicated by Fig. 1 of the drawings, wherein the wheel is free to rotate and also free to shift horizontally on the journal toward and against the car body when, during the travel of the car, the car body is moved or thrust sidewise toward the upright plane of the track rail with which that wheel is engaged. My present invention is not concerned with preventing body thrust pressure of the wheel hub against the car body. For means for preventing that form of hub pressure, I make reference to my Letters Patent of the United States No. 1,581,476, dated April 20, 1926; and No. 1,606,726, dated November 9, 1926; and Letters Patent of the United States, No. 1,720,077, granted to Harry W. Jones, July 9, 1929. In the cars of those patents, a transverse part of the hub extends across and bears against the end of the journal and prevents movement of the hub toward the car body.

I claim as my invention,

1. In a railway car of the kind described, the combination of car body longitudinal side members, two unitary axle bearings on each of said side members, axles in said bearings, wheels on said axles, the upper

part of each bearing being formed to seat on the adjacent upper face of the adjacent axle and the bearing opening being extended downward below the lower part of the axle

5 when the bearing is seated on the axle and said downward-extended part of said opening being wider than the upper part of the bearing.

2. In a railway car of the kind described, 10 the combination of car body longitudinal side members, two unitary axle bearings on each of said side members, axles in said bearings, wheels on said axles, the upper part of each bearing being formed to seat on the adjacent upper face of the adjacent axle and the bearing opening being extended downward and enlarged below the lower part of the axle when the bearing is seated on the axle.

15 3. In a railway car of the kind described, the combination of car body longitudinal side members, two unitary axle bearings on each of said side members, axles in said bearings, wheels on said axles, the upper part 20 of each bearing being formed to seat on the adjacent part of the adjacent axle and the bearing opening being extended downward below the lower part of the axle when the bearing is seated on the axle and said downward-extended part of said opening being wider than the diameter of the axle and wider than the bearing seat and the upper 25 parts of the lateral faces of said opening below the bearing seat being inclined toward each other.

4. In a railway car of the kind described, the combination of car body longitudinal side members, two unitary axle bearings on each of said side members, axles in said bearings, wheels on said axles, the upper part 30 of each bearing being formed to seat on the adjacent part of the adjacent axle and the bearing opening being extended downward below the lower part of the axle when the bearing is seated on the axle and said downward-extended part of said opening being wider than the diameter of the axle and the lateral faces of the part of said opening below the bearing seat having a plurality of 35 faces the upper part of each of which is inclined toward the other of said faces.

5. In a railway car of the kind described, the combination of car body longitudinal side members, two unitary axle bearings on each of said side members, axles in said bearings, wheels on said axles, the upper part 40 of each bearing being formed to seat on the adjacent part of the adjacent axle and the bearing opening being extended downward and enlarged below the lower part of the axle when the bearing is seated on the axle.

6. In a railway car of the kind described, the combination of car body longitudinal side members, two unitary axle bearings on each of said side members, axles in said bear-

ings, wheels on said axles, the upper part of each bearing being formed to seat on the adjacent part of the adjacent axle and the bearing opening being extended downward below the lower part of the axle when the bearing is seated on the axle and said downward-extended part of said opening being wider than the diameter of any part of the axle, the upper parts of the lateral faces below the bearing seat being inclined toward each other.

7. In a railway car of the kind described, the combination of car body longitudinal side members, two unitary axle bearings on each of said side members, axles in said bearings, wheels on said axles, the upper part of each bearing being formed to seat on the adjacent upper face of the adjacent axle and the bearing and the axle being formed for inter-engagement to hold the axle against relative endwise movement when the bearing is seated on the axle, and the bearing opening being extended downward and enlarged below the lower part of the axle when the bearing is seated on the axle.

8. In a railway car of the kind described, the combination of car body longitudinal side members, two unitary axle bearings on each of said side members, axles in said bearings, wheels on said axles, the upper part of each bearing being formed to seat on the adjacent upper face of the adjacent axle and the bearing and the axle being formed for inter-engagement to hold the axle against relative endwise movement when the bearing is seated on the axle and the bearing opening being extended downward and enlarged below the lower part of the axle when the bearing is seated on the axle.

9. In a railway car of the kind described, the combination of car body longitudinal side members, two axle bearings on each of said side members, axles in said bearings, wheels on said axles, each axle having within the adjacent bearing a circumferential collar and the upper part of each bearing having a transverse groove to receive said axle collar and said bearing being otherwise formed to seat on the adjacent part of the axle and the bearing opening being extended downward below the lower part of the axle when the bearing is seated on the axle and said downward-extended part of said opening being wider than the diameter of said collar.

10. In a railway car of the kind described, the combination of car body longitudinal side members, two axle bearings on each of said side members, axles in said bearings, wheels on said axles, each axle having within the adjacent bearing a circumferential collar and the upper part of each bearing having a transverse groove to receive said axle collar and said bearing being otherwise formed to seat on the adjacent part of the axle and the bearing opening being extended downward be-

- low the lower part of the axle when the bearing is seated on the axle and said downward extended part of said opening being wider than the diameter of any part of the axle.
- 5 11. In a railway car of the kind described, the combination of a longitudinal side member at each side of the car, two horizontal openings through each side member, a unitary axle bearing secured to each side member at each of said openings, axles in said bearings, the inner part of each bearing being formed to seat saddle-fashion on the upper face of the adjacent part of the axle and the bearing opening being extended downward below the lower part of the axle when the bearing is seated on the axle and said downward-extended part of said opening being wider than the upper part of said opening.
- 10 12. In a railway car of the kind described, the combination of a longitudinal side member at each side of the car, two horizontal openings in each side member, a unitary axle bearing secured to each side member at each of said openings and having a lateral extension, axles in said bearings, the inner part of each bearing being formed to seat saddle-fashion on the upper face of the adjacent part of the axle and the bearing opening being extended downward below the lower part of the axle when the bearing is seated on the axle and said downward-extended part of said opening being wider than the upper part of said opening.
- 15 13. In a railway car of the kind described, the combination of a longitudinal side member at each side of the car, two horizontal openings in each side member, a unitary axle bearing secured to each side member at each of said openings and having an upper lateral extension, axles in said bearings, the inner part of each bearing being formed to seat saddle-fashion on the upper face of the adjacent part of the axle and the bearing opening being extended downward below the lower part of the axle when the bearing is seated on the axle and said downward-extended part of said opening being wider than the upper part of said opening.
- 20 14. In a railway car of the kind described, the combination of a longitudinal side member at each side of the car, two horizontal openings through each side member, an axle bearing secured to each side member at each of said openings, and axles in said bearings, the inner part of each bearing and the adjacent part of the axle being formed for inter-engagement to hold the axle against relative endwise movement when the bearing is seated on the axle and the bearing opening being extended downward below the lower part of the axle when the bearing is seated on the axle and said downward-extended part of said opening being wider than the diameter of the axle and wider than the bearing seat.
- 25 15. In a railway car of the kind described, the combination of a side member at each side of the car, two horizontal openings through each side member, a unitary axle bearing secured to each side member at each of said openings, and axles in said bearings, the inner upper face of each bearing being formed to seat saddle-fashion on the upper part of the axle and the bearing opening being extended downward below the lower part of the axle when the bearing is seated on the axle, and said downward-extended part of said opening being wider than the upper part of said opening.
- 30 16. In a railway car of the kind described, the combination of structural metal longitudinal side members, two unitary axle bearings on each of said side members, axles in said bearings, and wheels on said axles, the upper part of each bearing being formed to seat on the adjacent upper face of the adjacent axle and the bearing opening being extended downward below the lower part of the axle when the bearing is seated on the axle and said downward-extended part of said opening being wider than the upper part of said opening.
- 35 17. In a railway car of the kind described, the combination of channel-form metal longitudinal side members, two transverse openings through the upright web of each side member, a unitary axle bearing on each side member at each of said openings, axles in said bearings, and wheels on said axles, the upper part of each bearing being formed to seat on the adjacent upper part of the adjacent axle and the bearing opening being extended downward and enlarged below the lower part of the axle when the bearing is seated on the axle.
- 40 18. In a railway car of the kind described, the combination of metal channel-form longitudinal side members, two transverse openings through the upright web of each side member, a unitary axle bearing secured to each side member between the flanges of the side member at each of said openings, axles in said bearings, and wheels on said axles, the upper part of each bearing being formed to seat on the upper face of the adjacent axle and the bearing opening being extended downward and enlarged below the lower part of the axle when the bearing is seated on the axle.
- 45 19. In a railway car of the kind described, the combination of metal channel-form longitudinal side members, two horizontal openings through each side member, an axle bearing secured to each side member between the channel-flanges at each of said openings, and axles in said bearings, the upper part of each bearing being formed to seat on the adjacent upper face of the adjacent axle and the bearing opening being extended downward and enlarged below the lower part of the axle when the bearing is seated on the axle.
- 50 20. In a railway car of the kind described, the combination of metal channel-form longitudinal side members, two horizontal openings through each side member, an axle bearing secured to each side member between the channel-flanges at each of said openings, and axles in said bearings, the upper part of each bearing being formed to seat on the adjacent upper face of the adjacent axle and the bearing opening being extended downward and enlarged below the lower part of the axle when the bearing is seated on the axle.
- 55 21. In a railway car of the kind described, the combination of metal channel-form longitudinal side members, two horizontal openings through each side member, an axle bearing secured to each side member between the channel-flanges at each of said openings, and axles in said bearings, the upper part of each bearing being formed to seat on the adjacent upper face of the adjacent axle and the bearing opening being extended downward and enlarged below the lower part of the axle when the bearing is seated on the axle.
- 60 22. In a railway car of the kind described, the combination of metal channel-form longitudinal side members, two horizontal openings through each side member, an axle bearing secured to each side member between the channel-flanges at each of said openings, and axles in said bearings, the upper part of each bearing being formed to seat on the adjacent upper face of the adjacent axle and the bearing opening being extended downward and enlarged below the lower part of the axle when the bearing is seated on the axle.
- 65 23. In a railway car of the kind described, the combination of metal channel-form longitudinal side members, two horizontal openings through each side member, an axle bearing secured to each side member between the channel-flanges at each of said openings, and axles in said bearings, the upper part of each bearing being formed to seat on the adjacent upper face of the adjacent axle and the bearing opening being extended downward and enlarged below the lower part of the axle when the bearing is seated on the axle.

- bearing and the axle being formed for inter-engagement to hold the axle against relative endwise movement when the bearing is seated on the axle, and the bearing opening being extended downward below the lower part of the axle when the bearing is seated on the axle.
20. In a railway car of the kind described, the combination of metal channel-form longitudinal side members, two horizontal openings through each side member, an axle bearing secured to each side member between the channel-flanges at each of said openings, and axles in said bearings, the upper part of each bearing being formed to seat on the adjacent upper face of the adjacent axle and the bearing and the axle being formed for inter-engagement to hold the axle against relative endwise movement when the bearing is seated on the axle, and the bearing opening being extended downward below the lower part of the axle when the bearing is seated on the axle, said lower extension of said opening being wider than the adjacent part of the 25 axle.
21. In a railway car of the kind described, the combination of metal channel-form longitudinal side members, two horizontal openings through each side member, an axle bearing secured to each side member between the channel-flanges at each of said openings, and axles in said bearings, the upper part of each bearing being formed to seat on the adjacent upper face of the adjacent axle and the bearing and the axle being formed for inter-engagement to hold the axle against relative endwise movement when the bearing is seated on the axle, and the bearing opening being extended downward below the lower part of the axle when the bearing is seated on the axle, said lower extension of said opening being wider than any part of the axle.
22. In a railway car of the kind described, the combination of metal channel-form longitudinal side members, two horizontal openings through each side member, an axle bearing secured to each side member between the channel-flanges at each of said openings, axles in said bearings, the upper part of each bearing being formed to seat on the adjacent upper face of the adjacent axle and the bearing and the axle being formed for inter-engagement to hold the axle against relative endwise movement when the bearing is seated on the axle, and the bearing opening being extended downward below the lower part of the axle when the bearing is seated on the axle, and said downward extended part of said opening being wider than the diameter of the axle and wider than the bearing seat and the upper parts of the lateral faces of said opening below the bearing seat being inclined toward the upright longitudinal plane of the 65 bearing axis.
23. In a railway car of the kind described, the combination of a car body, two unitary axle bearings stationary on each side of said body, axles in said bearings, wheels on said axles, the upper part of each bearing being formed to seat on the adjacent upper face of the adjacent axle and the bearing opening being extended downward and enlarged below the lower part of the axle when the bearing is seated on the axle.
24. In a railway car of the kind described, the combination of a car body, two axle bearings stationary at each side of said body, axles in said bearings, wheels on said axles, each axle having within the adjacent bearing a circumferential collar and the upper part of each bearing having a transverse groove to receive said axle collar and said bearing being otherwise formed to seat on the adjacent part of the axle and the bearing opening being extended downward below the lower part of the axle when the bearing is seated on the axle and said downward extended part of said opening being wider than the diameter of said collar.
25. In a railway car of the kind described, the combination of a car body, two axle bearings stationary on each side of said body, axles in said bearings, wheels on said axles, each axle having within the adjacent bearing a circumferential collar and the upper part of each bearing having a transverse groove to receive said axle collar and said bearing being otherwise formed to seat on the adjacent part of the axle and the bearing opening being extended downward below the lower part of the axle when the bearing is seated on the axle and said downward extended part of said opening being wider than the diameter of any part of the axle.
26. In a railway car of the kind described, the combination of channel-form side sills, each having two web openings, two axle bearings seated in each side sill between the side sill flanges and extending through the adjacent web opening, axles extending through said bearings and having collars adapted to engage said bearings during normal position to prevent endwise movement of the axle, and each bearing extending below the normal position of the axle far enough and being wide enough below said normal position to permit passing the axle endwise through the bearing when the axle is in the enlarged lower part of the bearing.
27. In a railway car of the kind described, the combination of a unitary axle bearing stationary at each side of the car and each having its upper part formed to seat on the upper part of the below-mentioned axle and having its lower part extended downward and enlarged to allow endwise passing of the entire axle, and an axle resting in and extending through each of said bearings and having a 130

part extending radially outward farther than the axle face on which the bearing seats.

28. In a railway car of the kind described, the combination of an axle bearing stationary at each side of the car and each having its upper part formed to seat on the upper part of the below-mentioned axle and having its lower part extended downward and enlarged to allow endwise passing of the entire axle, and an axle resting in and extending through said bearings, the axle and the upper part of the bearings being formed for inter-engagement to prevent endwise movement of the axle in the bearings when the bearings are seated on the axle.

29. In a railway car of the kind described, the combination of an axle bearing stationary at each side of the car and each having its upper part formed to seat on the upper part of the below-mentioned axle and having its lower part extended downward and enlarged to allow endwise passing of the entire axle, and an axle resting in and extending through said bearings, the axle being collared and the upper part of the bearings being grooved to form inter-engagement when the bearings are seated on the axle, whereby inter-engagement is made to prevent endwise movement of the axle in the bearings when the bearings are seated on the axle.

In testimony whereof I have signed my name, this 25th day of August, in the year one thousand nine hundred and thirty.

HUGH W. SANFORD.
